(57) **CLAIM**

The ornamental design for a removable decorative panel for a case as shown and described.

DESCRIPTION

FIG. 1 is a top perspective view of the removable decorative panel for a case;

FIG. 2 is a top plan view of the same;

FIG. 3 is a left side view of the same, the right side view being a mirror image thereof;

FIG. 4 is a bottom plan view of the same; and,

FIG. 5 is a rear elevational view of the same.

The broken away symbols and the long dash-short dash-short dash broken line in the drawings indicate the appearance of any portion of an article between the break lines that forms no portion of the claimed design. The bold dash broken lines are to illustrate stitching and form not part of the claimed design. The light dash broken lines in the drawings show the environment and form no part of the claimed design.
